(57) **CLAIM**

The ornamental design for a USB cable, as shown and described.

DESCRIPTION

FIG. 1 is a front view of a USB cable showing my new design;

FIG. 2 is a back view thereof;

FIG. 3 is a left side view thereof;

FIG. 4 is a right side view thereof;

FIG. 5 is a top view thereof;

FIG. 6 is a bottom view thereof; and,

FIG. 7 is a perspective view thereof.

The broken lines shown in the drawings depict portions of the USB cable in which the design is embodied that form no part of the claimed design.

The break lines and broken line bracket in the drawings indicate that the appearance of any portion of the article between the break lines forms no part of the claimed design. The broken line bracket forms no part of the claimed design.
